STARTING MECHANISM FOR INTERNAL-COMBUSTION ENGINES.

1,157,849.

Specification of Letters Patent.

Patented Oct. 26, 1915.

Application filed February 2, 1915. Serial No. 5,604.

To all whom it may concern:

Be it known that we, GREGORY C. DAVISON and JOHN W. ANDERSON, citizens of the United States, residing at New London, 5 in the county of New London and State of Connecticut, have invented certain new and useful Improvements in Starting Mechanism for Internal-Combustion Engines; and we do hereby declare the following to be a 10 full, clear, and exact description of the invention, such as will enable others skilled in the art to which it appertains to make and use the same.

This invention relates to starting mechanism 15 for internal combustion engines of the type employing compressed air as the starting medium, such air being admitted to the cylinders of the engine to act on the pistons therein.

20 The object of the invention is to provide such a starting mechanism employing pneumatically actuated air-inlet valves on the cylinders of the engine controlling the admission of compressed air to the cylinders 25 and a simple form of valve mechanism governing the supply of the actuating air to these pneumatically actuated valves, this valve mechanism requiring but a single cam to actuate it and being adapted for use in 30 starting the engine in either direction.

In accordance with the invention, each of a plurality of the cylinders of the engine is provided with a pneumatically actuated, air-inlet valve adapted when open to connect the cylinder on which it is mounted with the source of supply of compressed air. The several inlet valves are connected to a distributor consisting of a plurality of valves which may be mechanically actuated to admit air to or permit its exhaust from the corresponding inlet valve so as to open or close the latter. These valves of the distributor are arranged radially about a cam driven by the shaft of the engine so that 45 they may be actuated by the cam successively in the requisite order and with the requisite time intervals between. The manner of mounting the cam or the several valves with which the cam coacts is such 50 as to permit of varying the angular relation of the cam or the valves to the shaft of the engine so as to permit of adapting the starting mechanism for starting the engine

in either direction. Preferably, this is done by connecting the cam to the shaft which 55 drives it by means of an axially movable sleeve whose connection to one of the two coacting parts is made by means of a spiral thread. The several valves actuated by the cam are of a special construction involving 60 various features of novelty including means whereby these valves are normally held out of engagement with the cam but are automatically moved into engagement with the cam when the source of supply of compressed air is connected to the engine for 65 starting the latter.

These and other features of the invention will be better understood by reference to the following description taken in connection 70 with the accompanying drawings, which show the preferred embodiment of the invention.

In these drawings, Figure 1 is an elevation of a portion of an internal combustion 75 engine, Fig. 2 is an elevation, broken away and sectioned in part, of the distributor, Fig. 3 is a transverse section of the distributor and Fig. 4 is a sectional view of a form of air-inlet valve which may be employed on each of the cylinders.

Referring to these drawings, Fig. 1 illustrates an internal combustion engine having a plurality of cylinders, three of the cylinders being shown in the figure. The engine is adapted to be started by admitting compressed air to some or all of the cylinders and for this purpose each of a plurality of cylinders 7 is provided with an inlet valve 5 by which air is admitted to 85 the interior of the cylinder. This air is supplied through a pipe 6 which leads from a source of supply of compressed air and which is connected through ducts in the cylinder heads to each of the inlet valves 90 95. The valves 5 are arranged to be actuated pneumatically. For this purpose a construction such as is shown in Fig. 4 may be employed. By reference to that figure, it will be seen that the cylinder casting 7 is provided with an opening adapted to receive a valve casing consisting of two parts 8 and 9, secured together in axial alignment. Within this casing is a movable member 10 adapted to be actuated pneumatically 100 105 against the tension of a coiled spring 11, so

as to move a valve member 12 from its seat upon the inner end of the casing. A cap 13 secured to the cylinder casting at the end of the opening therein for the valve has a passage 14 therethrough by which air is admitted to and exhausted from the space in the rear of the movable member 10. As shown in Fig. 4, the part 9 of the casing for the valve has a plurality of openings there-
5 in for the entrance of air from the compressed air pipe, the flow of the compressed air from the pipe through these openings and into the cylinder being controlled by the movable valve member 12. This valve
10 member is opened by admission of air to the upper end of the movable member 10 through the passage 14 and when the passage 14 is connected to the atmosphere, the movable member 10 is returned to its ini-
15 tial position by the spring 11, thus closing the valve 12.

The admission of compressed air to the passages 14 of the several inlet valves so as to open those valves the proper length of time and in the proper sequence, is effected by a distributor whose movable member is driven by the shaft of the engine. This distributor is shown in detail in Figs. 2 and 3 and is shown mounted upon the casing 15 of the engine in Fig. 1. It may be mounted in any position convenient for manipulation and inspection and for connecting it to the engine shaft. This distributor consists of a plurality of valve mechanisms, each connected to a source of supply of compressed air and to one of the inlet valves 5 and a cam driven by the engine shaft and arranged to actuate the several valve mechanisms successively. In the drawings, the cam 16 is shown as mounted upon a shaft 17 supported in a suitable bearing in the casing 15 of the engine and carrying a gear 18 which meshes with a gear 19 on the engine shaft. It will be understood, however, that any other suitable driving means for the cam, suitably timed with respect to the engine shaft, may be adopted instead of that shown. Encircling the cam 16 is an annular support 20 having a plurality of valve mechanisms which are mounted thereon at equal distances apart. Each valve mechanism is provided with a suitable device, such for instance, as a roller 21 adapted to engage the periphery of the cam 16 so that the cam may actuate the valve. Each valve mechanism consists of a cylindrical casing 22 having an axial opening therethrough, one portion of which is substantially larger than the other portion. This opening is adapted to receive a movable valve member 23 which is movable to positions on one side and on the other side of a port 24. Below this port is another port 25 open to the atmosphere. The stem 26 of the valve member 23 is extended above and below the

valve member. Below the valve member it is provided with an enlargement 27 which serves as a guide movable in an opening in the support 20 and which carries the roller 21. Above the valve member 23, the stem 26 is provided with a head 28 and a spring 29 is coiled around the stem 26 between the head 28 and the wall formed by the contraction of the size of the opening in the casing 22. This enlarged portion of the opening in casing 22 is provided with a port 30.

The ports 30 of each of the several valve mechanisms grouped about the cam 16, are connected to the source of supply of compressed air by pipe 31. The ports 24 of the several valve mechanisms are connected by pipes 32, 33 and 34 to the passages 14 of the air-inlet valve 5.

The cam 16 is so mounted upon its shaft 17 as to permit of moving it angularly about the shaft 17 as desired and when the desired position of the cam has been selected it may be maintained in that angular position with reference to the shaft 17 throughout the operation of the engine and consequent rotation of shaft 17. For this purpose an axially movable sleeve is provided between the cam and the shaft, its connection to one of the two parts being made by a spiral thread. This sleeve is shown at 35. It is splined to the shaft 17 by means of the keys 36. On its exterior surface are a plurality of spirally arranged threads which are received in corresponding grooves in the opening through the hub 37 of the cam 16. The sleeve 35 may be moved axially as desired, either manually, pneumatically or in any other suitable manner. In the drawings, a hand lever is shown for this purpose at 38, this being pivotally mounted upon the casing of the engine and connected to the sleeve 35 by means of a short shaft 39. On the end of this short shaft is secured a collar 40 and a similar collar 41 is secured to the sleeve 35 by means of a flanged collar 42. Between the collars 40 and 41 are a plurality of balls 43.

The operation of the mechanism thus constructed will now be described. When the engine is not in use and when the engine is in normal operation, the several valve mechanisms are held from contact with the cam 16, which is rotated in accordance with the rotation of the engine shaft, the springs 29 serving to move the valve members 23 slightly so as to lift the rollers 21 from engagement with the cam. When it is desired to start the engine, a valve in the connection from the source of supply of compressed air is opened, thus admitting compressed air to the conduit 6 and to the several conduits 31 connected to the ports 30. The air so admitted through the ports 30 acts upon the upper surfaces of the valve members 23 so as to move those valve members and the

parts connected thereto radially inward against the tension of the springs 29, so carrying the rollers 21 into engagement with the cam 16. In the case of most of the 5 valve mechanisms, this inward movement of the valve member 23 will be very slight since the movement will be arrested by contact of the roller 21 with the periphery of the cam 16. One of the valve mechanisms, 10 however, will be in the position for coaction with the cutaway portion of the cam 16 and that one will be moved inwardly a greater distance, so that its valve member 23 will be moved past the port 24. This will permit 15 the flow of air from the source of supply through the pipes 31, port 30, the central opening in casing 22, port 24 and the pipe 32, 33 or 34 leading to the inlet valve of the corresponding cylinder and that 20 valve will be actuated so as to admit compressed air from the conduit 6 to the corresponding cylinder. The air thus admitted to the cylinder will act on the piston therein to start the rotation of the engine shaft 25 and as the latter so rotates, the cam 16 will be turned, thus carrying the cutaway portion of the cam around into coaction with the roller of another valve mechanism, resulting in the admission of compressed air 30 to another of the cylinders. As the cutaway portion of the cam passes beyond one of the rollers 21, that roller and the parts to which it is connected are moved outwardly so as to carry the corresponding 35 valve member 23 to a position between the ports 30 and 24. This closes the passage for the compressed air to the inlet valve previously supplied with air and connects that valve to the atmosphere through the port 24, 40 the opening in casing 22 and port 25, as a result of which the corresponding inlet valve is immediately closed by its spring 11. The several inlet valves will thus be actuated successively to open and admit air 45 to the cylinders and then close, thus causing rotation of the engine shaft until operation thereof in the normal manner is begun. Then the supply of compressed air is cut off and the springs 29 of the several valve members 50 of the distributor serve to lift the valve members out of coaction with the cam 16. Whenever it is desired to operate the engine in the opposite direction, the sleeve 35 is moved axially by means of the handle 38, 55 thus turning the cam 16 about the shaft 17 through a definite angular distance so that the cam 16 assumes a different angular position with relation to the shaft of the engine. Then the admission of air to the cylinders of the engine in the manner above described will cause operation of the engine in the reverse direction.

It will be understood that the distributor may be provided with any desired number 60 of valve mechanisms, but all or a number

less than all of these may be used as desired. As it is common to employ internal combustion engines having six cylinders, the distributor is illustrated as having six valve mechanisms, but it is only necessary to admit compressed air to three of the cylinders in order to start the engine. If this be done, the three valve mechanisms corresponding to the three cylinders which are not to be employed in starting may be disconnected. 70 75

By this construction, a single cam serves the purpose of controlling the actuation of all of the pneumatically operated valves by which compressed air is admitted to the cylinders of the engine for starting, and this one cam serves this purpose in starting the engine both in the forward and reverse directions. A very desirable simplification of the mechanism is thus effected and the adaptation of the mechanism for forward or reverse operation is accomplished by merely moving the sleeve on which the cam is mounted a predetermined distance in an axial direction. 80 85

What we claim is:

1. The combination of an internal combustion engine having a plurality of cylinders, a source of supply of compressed air, a pneumatically actuated air-inlet valve on each cylinder controlling the passage of air 90 from said source to the cylinder, a plurality of valves controlling the supply of compressed air to the inlet valves to actuate the latter, a rotary member operatively connected to the engine shaft and adapted to 95 actuate the controlling valves successively, and means for effecting an adjustment of the rotary member to vary the time of actuation of the air-inlet valves relative to the rotation of the engine shaft, said means 100 maintaining the rotary member operatively connected to the engine shaft when in its adjusted position; substantially as described.

2. The combination of an internal combustion engine having a plurality of cylinders, a source of supply of compressed air, a pneumatically actuated air-inlet valve on each cylinder controlling the passage of air from said source to the cylinder, a shaft 110 driven by the engine shaft, a cam driven thereby, an axially movable sleeve interposed between the cam and said shaft and connected to one of them by a spiral thread, and a plurality of valves arranged about the cam, adapted to be actuated successively 115 thereby and controlling the supply of compressed air to said inlet valves to actuate them; substantially as described.

3. The combination of an internal combustion engine having a plurality of cylinders, a source of supply of compressed air, a pneumatically actuated air-inlet valve on each cylinder controlling the passage of air from said source to the cylinder, a cam 125 driven by the engine shaft, a plurality of 130

- controlling valves arranged about said cam adapted to be actuated successively thereby and controlling the supply of compressed air to said inlet valves, means for holding the controlling valves normally out of coaction with the cam, and pneumatically operated means for moving the valves into coaction with the cam; substantially as described.
- 10 4. The combination of an internal combustion engine having a plurality of cylinders, a source of supply of compressed air, a pneumatically actuated air-inlet valve on each cylinder controlling the passage of air from said source to the cylinder, a cam driven by the engine shaft, a plurality of controlling valves arranged about said cam
- 5 and controlling the supply of compressed air to said inlet valves, operating means for said controlling valves adapted to be actuated successively by said cam, means normally holding said operating means out of engagement with the cam, and pneumatically operated means for moving said operating means into engagement with the cam, substantially as described.
- 15 In testimony whereof we affix our signatures, in presence of two witnesses.
